UNITED STATES PATENT OFFICE

WILLIAM E. WACKER, OF MAPLEWOOD, NEW JERSEY, ASSIGNOR TO AUGUST GOERTZ
& CO., INC., A CORPORATION OF NEW JERSEY

COSMETIC BOX

Application filed December 8, 1928. Serial No. 324,681.

This invention relates to improvements in cosmetic boxes or vanity cases; and the invention has for its principal object to provide a simple construction and assembly of parts comprising a body and cover sections hinged together, and a novel construction and arrangement of means for retaining cosmetic powder within the body section, together with means for discharging powder therefrom 10 when desired for use with a maximum of ease and convenience in handling.

Other objects of this invention, not at this time more particularly enumerated, will be clearly understood from the following detailed description of the same.

The invention is clearly illustrated in the accompanying drawings, in which:—

Fig. 1 is a perspective view of the box or case closed but with the powder discharge 20 orifice open for discharging powder;

Fig. 2 is a sectional view taken along line 2—2 of Fig. 1;

Fig. 3 is a transverse view of the body section with contained tray member looking towards the front of said body section, the powder box being removed;

Fig. 4 is a perspective view of the tray member and illustrates the manner of inserting the powder box therein;

Fig. 5 is a view looking at the tray member from below;

Fig. 6 is a plan view of the box or case open and shows the powder and rouge puffs removed from the same;

Fig. 7 is a view in front elevation of the body section, the powder discharge orifice being closed;

Fig. 8 is a view similar to Fig. 6 but illustrates the tray member with parts broken away removed from the body section; and

Fig. 9 is a sectional view of the body section looking toward the front thereof.

Similar characters of reference are employed in all of the hereinabove described views, to indicate corresponding parts.

Referring now to said drawings, the reference character 10 indicates a body section and 11 a cover section of a cosmetic box or vanity case, said sections being of substantially rectangular cross-section and hingedly

connected together. The body section 10 is provided in its front wall with a powder discharge orifice 12 shown as of elliptical shape although this orifice may have any other desired shape. Discharge orifice 12 is 55 adapted to be closed by a slide member or valve 13 positioned on the interior of the front wall of the body section 10. Slide member 13 has an outwardly struck boss 14 conforming to the orifice 12 which boss is adapted to snap into and snugly close the discharge orifice when the slide member 13 is moved so that this boss is positioned in registering relation with the discharge orifice. A button or knob 15 is positioned on the exterior of the front wall of the body section 10 for operating the slide member 13. Knob 15 has a shank 16 that extends through a slot 17 in the body section and is secured to the slide member 13. Manipulation of the knob 15 will close or open the discharge orifice 12 as desired.

A tray member 18 is adapted to be inserted into the body section 10. Tray member 18 has a downwardly extending peripheral flange 20 that is spaced from the walls of the tray member and which is connected to said walls by a curved bead-like connecting bridge portion 21. Tray member 18 is provided with an inwardly struck aperture 19 that registers with the discharge orifice 12 when this tray member is positioned within the body section 10. The peripheral flange 20 together with the bridge portion 21 and the outer walls of the tray member form a 75 groove or recess within which felt or other suitable substance 22 may be frictionally retained adjacent the aperture 19 for preventing powder emerging from this aperture from passing around and being lost or wasted 80 at the sides of the tray member. The felt 22 confines the powder in its passage from the aperture 19 to the discharge orifice 12 and prevents the undesired escape or waste thereof.

When the tray member 18 is inserted into the body section 10, the peripheral flange 20 resiliently engages the walls of the body section, thereby frictionally retaining this tray member within the body section. The tray 95

member extends somewhat above the side walls of the body section, thereby giving these walls a rounded or crowned appearance at the top and also the appearance of substantial thickness inasmuch as the tray member appears to be an integral portion of the body section. This construction gives the vanity box a neat and attractive appearance when opened.

- 10 A partition 23 extends across the interior of the tray member 18 and has tongues at its ends fixed in apertures in the opposite walls of this member. Partition 23 divides the tray member into two parts one of which is 15 adapted to receive a rouge pan 24 containing a rouge cake 25 and the other a powder box 26 containing suitable cosmetic powder. The rouge pan 24 and powder box 26 fit snugly within the tray member and are frictionally 20 retained within this member. Rouge pan 24 may be readily removed from the tray member when desired, however, as for the purpose of inserting refills by merely prying out this pan with a tool inserted between a 25 corner of this pan and the partition 23. One or more corners of the powder box 26 may be beveled as at 27 to facilitate the easy removal of this box when desired, as for the purpose of inserting a refill.
- 30 Powder box 26 is made of paper, cardboard or any other suitable material and is a unitary structure without a lid. The side wall of the powder box 26 is adapted to be punctured to provide an opening 28 through which the 35 powder 30 emerges. Ordinarily the side wall of the powder box may be weakened at the location of the opening 28 so that this opening may readily be obtained as by pressing a hard instrument against such weakened side 40 wall. Also, the mere insertion of the powder box into the tray member will cause the ragged inwardly struck edges of the aperture 19 of the tray member to puncture the side wall of the powder box, thereby providing 45 the opening 28.

Cover section 11 may have a mirror 31 retained upon its inner surface in any well known manner. Instead of the mirror 31, an ornamental plaque or other desirable device may be positioned within the cover section. A catch 32 provided on the front wall of the cover section 10 is adapted to engage a lug 33 formed on the front wall of the body section, to thereby retain the vanity case in 50 closed condition. With the vanity case closed, there is sufficient space between the powder box 26 and mirror 31 for a powder puff 34. Also, there is sufficient space between the rouge cake 25 and mirror 31 for a 55 rouge puff 35.

In operation, to obtain powder from the vanity case it is merely necessary to operate the knob 15 so as to open the discharge orifice 12, whereupon any desired quantity 60 of powder may be readily shaken from the

vanity case without the necessity of opening the case. Owing to the relative small size of the discharge orifice, an excessively rapid discharge of powder is impossible, thereby preventing the spilling or wasting thereof. 70 Felt 22 confines powder 30 and causes it to pass directly from aperture 19 to the discharge orifice. It will be apparent that the discharge orifice may be at the side of the vanity case instead of at the front if desired. 75

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 80

What is claimed is:

1. In a vanity case comprising, a body section having a powder discharge orifice and a cover section hinged to said body section, a tray member within said body section, and having an aperture registering with said powder discharge aperture, a powder box carried by said tray member, said powder box having an opening communicating through said tray member aperture with said discharge orifice and valve means operable from the exterior of said body section for opening or closing said discharge orifice. 95
2. In a vanity case comprising, a body section having a powder discharge orifice on the outside thereof and a cover section hinged to said body section, a tray member within said body section, a powder box carried by said tray member, said powder box and tray member having openings communicating with said discharge orifice, a slide member for closing said discharge orifice and a knob for operating said slide member. 100
3. In a vanity case comprising, a body section and a cover section hinged to said body section, a tray member within said body section, said tray member having a peripheral flange spaced from the sides of said tray and frictionally engaging the inner walls of said body section, said flange being connected to the sides of said tray by an upper curved bridge portion projecting outwardly of said body section for telescoping into said cover section in guiding relation to the latter, and a cosmetic container carried by said tray member and frictionally retained therein. 110
4. In a vanity case comprising, a body section and a cover section hinged to said body section, a tray member within said body section, said tray member having a peripheral flange spaced from the sides of said tray and frictionally engaging the inner walls of said body section, said flange being connected to the sides of said tray by an upper curved bridge portion, a powder box carried by said tray member, said powder box, tray member 115
- 120
- 125
- 130

and body section having communicating apertures, and means retained between the side of said tray member and the peripheral flange thereof for conducting powder from the powder box and tray member apertures to the aperture in said body section.

5. In a vanity case comprising, a body section and a cover section hinged to said body section, a tray member within said body section, said tray member having a peripheral flange spaced from the sides of said tray and frictionally engaging the inner walls of said body section, said flange being connected to the sides of said tray by an upper curved 10 bridge portion, a powder box carried by said tray member, said powder box, tray member and body section having communicating apertures, means retained between the side of said tray member and the peripheral flange 15 thereof for conducting powder from the powder box and tray member apertures to the aperture in said body section and a valve 20 operable from the exterior of said body section for controlling the flow of powder from 25 said powder box.

In testimony that I claim the invention set forth above I have hereunto set my hand this 4th day of December, 1928.

WILLIAM E. WACKER.
